TRANSOM CONTROLLER

Charles W. Ward, Los Angeles, Calif.

Application March 9, 1938, Serial No. 194,973

1 Claim. (Cl. 268—113)

This invention relates to transoms and more particularly to improvements in transom actuating and locking means.

An object of the invention is to provide a simple, 5 practical and inexpensive device of the character described.

Another object is to provide a transom actuating and locking means which may be attached to the ordinary transom without changing its construction.

Another object is to provide transom actuating and locking means which can be operated with one hand.

Other objects and advantages will appear and 15 be brought out more fully in the following specification, reference being had to the accompanying drawing wherein.

Fig. 1 is a side view of a door jamb and transom illustrating my invention; and

Fig. 2 is a fragmentary front view of the same.

Referring more particularly to the drawing, I 20 show a door jamb 5, a door member 6, a transom 7 having a hinge 8 secured to a lower frame member 9 of the transom and door member 6, a bracket 10 suitably secured to transom 7 near the upper portion thereof and has an arm 11 extending over door jamb 5. A bracket 12 suitably affixed to door jamb 5 behind arm 11 and carries a pulley 13 over which passes a cord 14, the upper 25 end of which is secured to arm 11. A slide rod 15 is secured by brackets 16 to door jamb 5 and carries a slider 17 having a locking member 18 pivoted thereto at 19. Number 18 has a finger aperture 20 and a locking tip 21 and a spring 22 and is secured to the lower end of cord 14.

From this construction, it will be apparent that 30 spring 22 keeps locking member 18 locked against rod 15 by the pressure of tip 21 against rod 15, but may be released therefrom by a downward pull.

Door member 6 has a recess 23 in which is located a tubular member 24 having a compression spring 25 therein, the upper end of which bears against a plate 26 suitably recessed in transom frame member 9.

From this construction, it will be apparent that 5 the pressure of spring 25 will urge transom 9 into open position and that the transom will open by merely releasing locking member 18 from rod 15 and this can be done by a simple manipulation 10 of the locking member with one hand.

It will be understood that the foregoing description is illustrative only of my invention and that changes and modifications may be made without departing from the spirit and scope of 15 the subjoined claim.

Having described my invention, what I claim is:

A device of the character described, comprising 20 a transom having its lower end hinged to a door frame, a spring normally holding said transom open, an arm carried by the upper end of the transom and extending laterally over the side of the door frame, a pulley carried by the door frame in horizontal alignment with the arm carried by 25 the transom, a rod carried by the door frame below the pulley and spaced from the frame, a slider of U-shape form straddling said rod and freely movable thereon, a cable connected to the arm carried by the transom and passing over 30 the pulley and connected to the slider, a locking member intermediately pivoted between the outer ends of the arms of the slider, a locking tip carried by the inner end of the locking member and engaging the rod, a finger grip aperture in the 35 locking member beyond the slider, and a spring engaging the locking member beyond its pivot for normally holding the locking tip in engagement with the rod.

CHARLES W. WARD.
